UNITED STATES PATENT OFFICE.

GUSTAV WITT, OF ERFURT, GERMANY.

NEWSPAPER OR LIKE HOLDER.

SPECIFICATION forming part of Letters Patent No. 625,231, dated May 16, 1899.

Application filed January 7, 1899. Serial No. 701,497. (No model.)

To all whom it may concern:

Be it known that I, GUSTAV WITT, sanitary inspector, a subject of the King of Prussia, Emperor of Germany, residing at Erfurt, in the Kingdom of Prussia and German Empire, have invented certain new and useful Improvements in Newspaper or Like Holders, of which the following is a specification.

My invention relates to newspaper and like holders and is illustrated in the accompanying drawings, in which—

Figure 1 is a plan. Fig. 2 shows the holder open. Fig. 3 is a section on the line 1 1, Fig. 1; and Fig. 4 is a detail view.

One of the clamp members 1 is provided at its lower end with a handle 2 and with lateral spring-hinges 3, connecting it to the upper clamp member 4.

The lower clamp member 1 is beveled off along one side edge, as shown at 1^a, Fig. 3, and the springs attached to said member are each provided with an upwardly-bent portion 3^a, which terminate in pintle-bearings for the two hinge members. The upwardly-bent portions 3^a of the lower hinge members normally lie away from and out of contact with the said beveled-off side 1^a; but these parts of the springs are sufficiently elastic or springy to enable the upper clamp member 4 to be shifted laterally, so as to cause a disengagement of the locking devices, as will herein-after appear.

Pins 5 on the lower member 1 are formed with teeth on their sides and chamfered and pointed at the top for the purpose of enabling them easily to pass through the paper to be secured.

The upper member 4 has secured to one edge thereof metal plates 6, and adjacent to each plate the said member 4 is provided with a facing hole or recess 7 to receive the pins 5 of the lower member 1 when the two members are closed, and the said plates are each provided with a tooth-shaped projection adapted to engage with the teeth of the pins 5, as clearly shown in Fig. 4 of the drawings.

Both members 1 and 4 are provided on their inner surface with longitudinal recesses or grooves 8 and 9, whereby it is possible to secure the papers firmly by means of the outer edge of the clamp or holder.

When the holder is to be used, it is first

opened and the edge of the paper to be secured is pressed on the points of the pins 5. Then the other member 4 is firmly pressed against the lower member 1, whereby the pins 5 penetrate into the holes 7, and these teeth engage with the teeth of the metallic plates 6, whereby both jaws are held fast and any falling out of the papers is completely prevented.

When it is desired to add new papers or to remove old ones, it is sufficient to exercise a lateral pressure against the center of the upper member 4 in the right-hand direction, as shown by the arrow 11, Fig. 3, in order to disengage the teeth, whereupon the holder can be opened.

Having now particularly described and ascertained the nature of my invention and in what manner the same is to be performed, I declare that what I claim is—

1. A paper or like holder, comprising two members adapted to be folded one upon the other, yielding hinges connecting said members, at one side to enable one member to be shifted laterally with respect to the other member, and suitable locking means carried by the said members on that side opposite the said hinges, said locking means being disengaged by the lateral shifting of one of said members, substantially as described.

2. A paper or like holder, comprising two members adapted to be folded one upon the other, yielding hinges connecting said members at one side, so as to enable one member to be shifted laterally with respect to the other member, toothed pins on one of said members, and fixed lock-plates on the opposite member, with which said pins engage to hold the two members in locked engagement, said lock-plates being disengaged from the toothed pins by the lateral shifting of one of the members, substantially as described.

3. A paper or like holder comprising two clamping members adapted to be folded one upon the other, yielding hinges connecting said members at one side, so as to enable one member to be shifted laterally with respect to the other member, fixed lock-plates carried by the shiftable member on that side opposite the said hinges and an opening adjacent to each of said plates, and toothed pins on the opposite member, arranged to pass into

said openings and engage with the lock-
plates, said lock-plates being disengaged from
the toothed pins by the lateral shifting of the
said shiftable member.

- 5 4. A paper or like holder comprising two
clamping members adapted to be folded one
upon the other, and one of said members be-
ing provided with a beveled side edge, hinges
connecting said clamping members adjacent
to said beveled edge, one part of each hinge
being movable to and from the said beveled
edge of the clamping member to enable one
member to be shifted laterally with respect

to the opposite member, and suitable lock-
ing means carried by the said clamping mem- 15
bers respectively, and disengaged by the lat-
eral shifting of one of the members, substan-
tially as described.

In testimony whereof I have hereunto set
my hand in presence of two subscribing wit- 20
nesses.

GUSTAV WITT.
